UNITED STATES PATENT OFFICE.

SIGMUND JOSEPH PENTLER AND OTTO R. SHORT, OF WAUSAU, WISCONSIN.

STITCHED-DOWN-SHOE CONSTRUCTION.

1,315,637.

Specification of Letters Patent. Patented Sept. 9, 1919.

Application filed April 12, 1919. Serial No. 289,579.

To all whom it may concern:

Be it known that we, SIGMUND JOSEPH PENTLER and OTTO R. SHORT, citizens of the United States, and residents of Wausau, in 5 the county of Marathon and State of Wisconsin, have invented certain new and useful Improvements in Stitched-Down-Shoe Construction; and we do hereby declare that the following is a full, clear, and exact 10 description thereof.

Our invention relates to new and useful improvements in the fastening of the middle sole to the inner sole of a stitched-down shoe.

15 It is highly desirable to provide a means of fastening the middle sole to the inner sole in a manner which is more secure and permanent in nature than the cement or other adhesive material which has been heretofore used and which avoids the occurrence 20 of clenched fastening projections on the foot engaging surface of the inner sole.

25 It is the object of our invention to provide an arrangement which may be most readily and conveniently effected to secure the middle sole to the inner sole in a manner embodying the aforerecited advantages.

30 More particularly, it is our object to provide the inner sole with means which will firmly secure the middle sole in place after the same is applied thereto.

35 With the above and other objects in view, which will be apparent as the description proceeds, our invention resides in the novel features of construction, combination and arrangement of parts as hereinafter described and defined by the appended claim, it being understood that changes in the precise embodiment might be made by those 40 skilled in the art, without departing from the spirit of the invention.

In the accompanying drawings:

Figure 1 represents a shoe, partly in section and partly in side elevation, in the process 45 of manufacture.

Fig. 2 is a plan view of the inner sole.

Fig. 3 is a sectional view through the inner sole using a modified form of fastening means, and

50 Fig. 4 is a view similar to Fig. 3 but using a further modified form of fastening means.

Referring now more particularly to the drawings, 5 designates the upper of a stitched-down shoe, which is lasted on an inner sole comprising upper and lower sections 6 and 7 respectively connected in the

usual manner by stitching 8 along their marginal edges, it being appreciated that the sections of the inner sole are sewed together as a unit prior to lasting the upper thereon. 60

In carrying out our invention, fastening members are passed through the lower section of the inner sole having retaining portions which are disposed between the sections of the inner soles when the same are 65 sewed together, said retaining portions being thus embedded in the completed inner sole. In Fig. 1, these fastener members are similar in type to common paper fasteners, each comprising a flat head portion 9 disposed between the inner sole sections and having a flattened pair of prongs 10 extending therefrom through the bottom section of the inner sole and adapted to pass through suitable registering openings 11 in 70 the middle sole 12 when the same is applied to the inner sole. After the middle sole is applied the free end portions of the prongs are bent laterally at 13 to lie against the bottom face of the middle sole and thus 75 effect a permanent and effective securement of the middle sole to the inner sole in a manner embodying economy and manufacturing steps, and conduced to a desired flat and comfortable shape of the sole portion 80 of the completed shoe.

As shown in Fig. 3, the fastening means may comprise nails having their heads 14 disposed between the section of the inner soles and having their shanks 15 extending 90 through the bottom section 7 to be passed through the middle sole as it is applied and clenched on the bottom face of the middle sole.

We may also utilize cords 16 as the fastening members, each cord being passed through a pair of openings in the bottom section 7, the bight of the cord between the openings forming the retaining portion of the fastening member. In the use of said 100 cords they would be passed through previously formed openings in the middle sole, their ends being tied together on the bottom of the middle sole.

It will be appreciated that any other single fastening means may be employed which carries out the essential idea of our invention, consisting in the utilization of fastening members passed through the lower section of the inner sole and having their retaining portions disposed between the layers of the inner sole to thus afford a smooth 105 110

expanse of the foot engaging surface of the inner sole.

What is claimed is:

In a stitched down shoe, the combination 5 with an inner sole comprising a pair of sections and a middle sole of fastening members passed through the lower section of the inner sole and through the middle sole and having retaining portions engaging the

bottom face of the middle sole and the top 10 face of the lower section of the inner sole.

In testimony that we claim the foregoing we have hereunto set our hands at Wausau, in the county of Marathon and State of Wisconsin.

SIGMUND JOSEPH PENTLER.
OTTO R. SHORT.
